[57] CLAIM

The ornamental design for a winged lion-shaped toy, as
shown and described.

DESCRIPTION

FIG. 1 is a front perspective view of a winged lion-shaped toy, showing my new design;

FIG. 2 is a left-hand side elevational view thereof, the
right-hand side elevational view being a mirror copy of
this view;

FIG. 3 is a front elevational view thereof;

FIG. 4 is a rear elevational view thereof;

FIG. 5 is a top plan view thereof; and,

FIG. 6 is a bottom plan view thereof.

FIG. 1

FIG. 2

FIG. 3

FIG. 4

FIG. 5

FIG. 6
